UNITED STATES PATENT OFFICE

ROBERT H. VAN SANT, OF CHICAGO, ILLINOIS

APPLICATOR FOR TOILET PREPARATIONS

Application filed April 5, 1928. Serial No. 267,575.

This invention relates to applicators of the type used in applying toilet preparations and treating the skin; and it has for its principal object to facilitate the treatment of shaven and close clipped skin to prevent ingrown hair and other unpleasant consequences of shaving and clipping.

The preferred embodiment of the invention is shown in the accompanying drawings, 10 in which

Fig. 1 is a central vertical section through a package including the applicator;

Fig. 2 is a plan view of the applicator; and

Fig. 3 is a transverse section taken on the 15 line 3—3 of Fig. 2.

The package includes a jar 10, a powder puff 11 and a cover 12. The jar is provided with two distinct constrictions at 13 and 14, and between them is a seat 15 with which 20 the marginal portion of the puff 11 is engaged.

The puff is composed of an inner filler 16, a casing 17, and a strap 18.

The filler may be of cotton linters, or other 25 suitable pad-forming material. The casing is made of two discs of terry cloth, Turkish toweling, or the like, with their edges turned inwardly and stitched together at 19. The strap is made of suitable braid, and its ends 30 are stitched between the inturned edges of the casing.

The terry cloth or the like is characterized by a long nap composed of uncut loops of yarn, but such a nap can, of course, be created on other material which may be thus 35 made suitable for the present purpose.

A powder puff having a nap formed of loops retains the powder when applied thereto, and therefore facilitates the application 40 of the powder to the skin. In rubbing a shaven or close clipped skin with such a puff the loops catch the individual hairs and deposit a small quantity of powder between the hair and the epidermis. Both the pulling 45 of the hair to a normal position and the application of the powder thereto tends to prevent ingrowing hairs. It also stimulates a healthy circulation and assists nature in restoring the damage done to the skin in removing the natural protecting covering.

A puff made of terry cloth, or the like, is easily washed or otherwise cleansed, and thus kept in a clean sanitary condition.

In some instances it will be desirable to increase the stiffness of the applicator and 55 this may be accomplished by inserting one or more discs 20 of suitable material such as grenadine or celluloid.

I claim as my invention—

1. An applicator for applying toilet powder to shaven or clipped skin, comprising a pair of superimposed peripherally connected layers of woven material having an exterior surface of uncut loops, stiffening material between the layers of woven material, padding 60 between the stiffening material and the layers of woven material, and a finger strap 65 arching across one face of the device and having its ends inserted between and secured to the layers of woven material. 70

2. A powder puff provided with an exterior nap surface of uncut loops having the property of retaining toilet powder applied thereto and of applying the retained powder to the skin of a person when used in the ordinary manner of using a powder puff, the outer and free closed end portions of said uncut loops also having the property of catching about the free ends of short close cut hairs and pulling them in an outstanding position and at the same time depositing retained powder around the outstanding hairs and upon the skin of the person. 75 80

In testimony whereof I affix my signature.
